UNITED STATES PATENT OFFICE.

AUSTIN D. HOFFMAN, OF CHICAGO, ILLINOIS, ASSIGNOR OF TWO-THIRDS HIS
RIGHT TO CARLOS A. COOK AND CHARLES E. COBURN, OF SAME PLACE.

IMPROVEMENT IN REGISTERING-MACHINES.

Specification forming part of Letters Patent No. **151,489**, dated June 2, 1874; application filed
March 18, 1874.

To all whom it may concern:

Be it known that I, AUSTIN D. HOFFMAN, of Chicago, in the county of Cook and State of Illinois, have invented an Improvement in Printers' Registers, of which the following is a specification:

The present invention relates to a counting or registering device which is to be attached to a printing-press to register the number of copies printed; and its nature consists in the employment of a series of carrying-arms, pivoted eccentrically to the pins or posts of the ratchet-wheels, and provided with wrists, which run in notches in the ratchet-wheels, that the arms may be held in position to rotate their respective wheels, and at the same time be drawn in past the peripheries of the wheels, and thus be out of the way of the other arms.

The faces of the wheels are provided with figures, and when turned on their respective pins or posts the figures are exposed to view.

I know that adders, counters, or registers have been constructed so that one wheel will turn another, and register units, tens, hundreds, &c.; therefore, I do not claim numbering by a series of wheels carrying figures, but confine myself to the devices for operating the wheels, as hereinafter shown and described.

In the drawing, Figure 1 is an inside view of the face-plate, ratchet-wheels, and eccentric arms; Fig. 2, a view of the opposite side of the face-plate, showing the holes therein for exposing to view the figures of the wheels. Fig. 3 represents the notch in the wheel for the eccentric arm to slide in. Fig. 4 represents the wrists of the arm sliding in the slot of the wheel.

A represents a face-plate, which is provided with pins or posts I, of lengths corresponding to the thicknesses of the wheels B C D E, and a series of holes, K, corresponding to the number of wheels. The several wheels are provided with ten ratchets, as shown, and with central holes, through which the pins or posts I pass, and they are respectively provided on their faces adjoining the plate A with the fig-

ures 1 2 3 4 5 6 7 8 9 0. A lever-arm, G, is provided with a spring, S, which passes through it and into a slot, N, at L. This arrangement is such that when the arm G is brought down, as indicated by dart X, the end Z will turn the wheel B far enough to expose the next figure on its face to view in its respective hole on its face-plate. When wheel B is completing its revolution its eccentric arm turns the wheel C far enough to expose the next figure on its face to view through its respective hole. The operation is continued until all the wheels are turned.

The arrangement, as shown, will count ninety-nine thousand nine hundred and ninety-nine.

The arms P, being pivoted eccentrically on the pins or posts I, extend outwardly at the proper place to turn the proper wheel; but when they are brought to the opposite side of the wheel they are drawn in to clear the wheel first turned.

To hold the eccentric arms P in place, and to carry them round, notches a, Fig. 3, are formed in the teeth of the wheels, and nibs b, Fig. 4, are formed on the outer ends of the said arms to run in the groove a; the latter being longer than the wrist allows the wheels to turn without binding.

No particular instruction is required to put the device into use, the plates A being fastened to any part of a press, or other mechanism requiring a register, so that the lever-arm G will have given to it a sufficient reciprocating motion to turn the wheel B.

I claim, and desire to secure by Letters Patent—

The carrying-arms P, provided with nibs b, and pivoted eccentrically on the fixed pins I, in combination with the ratchet-wheels, having slots a, substantially as and for the purpose specified.

AUSTIN D. HOFFMAN.
